Rev. W. Campbell

FIG. 6.

7. INVENTOR.
Herbert O. Phillips.
By Charles T. Hannigan,
Attorney.

UNITED STATES PATENT OFFICE.

HERBERT O. PHILLIPS, OF WARWICK, RHODE ISLAND.

DEVICE FOR REGULATING THE ELECTRIC SPARK OF GASOLENE-ENGINES.

No. 835,982.

Specification of Letters Patent.

Patented Nov. 13, 1906.

Application filed December 19, 1905. Serial No. 292,470.

To all whom it may concern:

Be it known that I, HERBERT O. PHILLIPS, a citizen of the United States, residing at the town of Warwick, in the county of Kent and 5 State of Rhode Island, have invented certain new and useful Improvements in Devices for Regulating the Electric Spark of Gasolene-Engines, of which the following is a specification.

- 10 This invention is for use on that class of gasolene-engines having a make-and-break spark-plug, the device being mounted in the side of the engine-cylinder and arranged to trip the latch-lever, which is pivoted on the 15 reciprocating bar of the eccentric-rod connection; and the object of the device is to permit of regulating the proper time in making the electric spark for firing to increase the power or slacken the speed of the engine, as 20 may be desired.

The invention consists of the novel construction, arrangement, and combination of parts as hereinafter described and claimed.

- In the accompanying sheet of drawings, 25 Figure 1 represents a perspective view of the device embodying my improvements. Fig. 2 is a side sectional view, taken in line $x-x$ of Fig. 3, illustrating the device secured in the side of the engine-cylinder and with its cover 30 removed and showing the contact-plug and its cam for operating the same. Fig. 3 is a view, partly in section and partly in elevation, taken in line $y-y$ of Fig. 2. Fig. 4 is a perspective view of the operating-cam. Fig. 35 5 is a partial view of a gasolene-engine cylinder having my improved device mounted thereon and also illustrating the relative position of the latch-lever in contact with the device prior to the spark-firing. Fig. 6 is a 40 similar view illustrating the relative position of parts, as after the spark-firing. Fig. 7 is a detail view of an ordinary make-and-break spark-plug and its rocker-arm connections.

Like reference characters indicate like 45 parts.

a designates a narrow metallic block having an integral stem a' , which is provided with an exterior screw-threaded portion a^2 to engage thereby in a threaded opening 50 formed in the side of the engine-cylinder b .

c is a nut mounted on the threaded portion of the stem a' and arranged to impinge against the cylinder in holding the block firmly in position thereon.

55 The block a is provided with a circular recess a^3 and an opening a^4 entering the same.

The recess a^3 is screw-threaded to receive the threaded portion of a disk d , which forms a cover to close said recess. The block a and its cover d are each provided with a circular 60 opening formed opposite each other to receive a rod e , upon which is secured a cam e' .

The cam e' disposes a series of flat surfaces 1, 2, 3, 4, and 5, arranged to contact upon the enlarged head f of a pin f' .

65 The opening a^4 of the block a is provided with a screw-threaded portion to engage thereby with a threaded nut g . This nut g has an opening therethrough to loosely receive the shank portion of the pin f' .

70 h is a coil-spring interposed between the nut g and pin f' and arranged to keep the head of the latter in contact with either of the flat surfaces 1, 2, 3, 4, and 5 of the cam e' .

Around the outer edge of the disk-cover d 75 is provided index-marks, as at d' d' in Fig. 1, which marks correspond in number with the series of contact-surfaces of the cam e' .

On the projecting portion of the cam-rod e is secured an index-pointer i and sleeve j , re- 80 spectively, and which latter member acts as a handle to operate the device.

Each of the cam-surfaces 1, 2, 3, 4, and 5 increase successively in distance from the axial center of the cam, so that by rotating the 85 rod e the cam causes the pin f' to move inwardly or outwardly of the block to the fixed position desired to operate in tripping the latch-lever k either early or late to fire the electric spark.

90 In Fig. 2 I show the cam set to correspond to the index-mark 3' in Fig. 1 and which registers the medium position for firing the spark. In Fig. 2 the surface 1 of the cam represents the slowest position for firing 95 the spark. Thus as the cam is set in the 3 position, as shown in said figure, it indicates a quicker position for firing before the piston reaches the end of its upward stroke.

In starting the engine the index-finger i is 100 at the index-point 5' and the highest part of the cam in contact upon the head of the pin f' .

105 Referring to Fig. 5, l is the eccentric-rod connection to the reciprocating-bar m , which carries the bell-crank or latch lever k . On the bar m is secured a flat spring n , to force said lever k in an upward position and against a shoulder formed in the bar m , as at a point m' . m^2 is a rod having one end secured in the bar m and its opposite portion mounted in the hub of a bracket o , which is 110

secured to the cylinder-head b' . p is a coil push-spring interposed between the hub of the bracket o and a collar q , which is loosely mounted on the rod m^2 . In one of the guide-
5 plates r of the bar m is secured a rod s , which forms a stop for the rocker-arm t to bear against after the spark has been fired. This arm t is beneath and forced in contact with the collar q by a coil-spring u . The rocker-
10 arm t is secured upon a short shaft t' , which enters through the side of the cylinder b , and on the inner portion of said arm t' is secured a second rocker-arm t^2 , that contacts with the spindle v of the spark-plug w .

15 These parts last described represent the common construction to operate in conjunction with the usual fixed bolt (not shown) for tripping the latch-lever k in making the spark.

20 Assuming that the eccentric (not shown) has nearly reached the upper end of its stroke, the vertical arm of the latch-lever k first contacts with and forces the collar q upwardly, thereby causing the spring - pressed
25 rocker-arm t to follow beneath and in contact with said collar, and at the same time the inner rocker-arm t^2 will have come in contact with the firing-pin v , and thus the electrodes come together and complete the circuit. After this movement of parts as de-
30 scribed, as the eccentric continues to carry its bar m upward the remainder of its stroke, the horizontal arm of the latch-lever k contacts with the projecting portion of the pin f'
35 of the block a , causing said lever to be released from connection with the collar q , and the spring p , being of greater tension than that of the spring u , instantly forces said collar down upon and causes the arm t to again bear upon
40 the end of the rod s in the position shown in Fig. 6, thus causing a separation of the electrodes and breaking the circuit.

45 From this description it will be understood that my device readily permits of raising or lowering the contact-pin f' to trip the latch-lever in making an early or late spark firing in explosive engines having a make-and-break spark-plug, according to the power required of the engine.

What I claim, and desire to secure by Letters Patent, is—

1. The herein-described device, comprising a block having an integral screw-threaded stem and said block provided with a recess; a disk-cover secured on said block and provided with a series of index-marks; a rod loosely mounted and projecting through said block and its said cover; an index-finger secured on said rod; a cam secured on said rod within the recess of said block, and said cam disposing a series of flat surfaces, each of which increases successively from and around the axial center of said rod; a pin loosely mounted in said block, projecting therefrom and having an enlarged integral head, and a coil-spring interposed between said block and the head of said pin and adapted to force the latter in contact with either flat surface of said cam, substantially as shown and for the purpose specified.

2. In a gasoline-engine having a spark-plug and a latch-lever for tripping the releasing mechanism to make or break the electric spark of said plug, the combination therewith, of a block adapted to be secured on the engine-cylinder and provided with a recess, and an opening entering the same, respectively; a spring-pressed pin mounted in the opening of said block, projecting therefrom and arranged to trip the latch-lever of the releasing mechanism; a disk-cover secured on said block and provided with a series of index-marks; a rod loosely mounted on said cover and said block; an index-finger secured on said rod; a cam secured on said rod within the recess of said block, and said cam having a series of flat surfaces arranged to contact upon the pin, whereby the same is moved either inwardly or outwardly from the block to make an early or late tripping contact with the latch-lever, substantially as set forth.

In testimony whereof I affix my signature in presence of two witnesses.

HERBERT O. PHILLIPS.
